UNITED STATES PATENT OFFICE.

EMANUEL SPREEKMEESTER, OF AMSTERDAM, NETHERLANDS.

PROPELLER.

1,413,296.

Specification of Letters Patent. Patented Apr. 18, 1922.

Application filed August 16, 1919. Serial No. 318,029.

To all whom it may concern:

Be it known that I, EMANUEL SPREEKMEESTER, a subject of the Queen of the Netherlands, residing at Amsterdam, the Netherlands, 114 Ruysdaelstraat, have invented certain new and useful Improvements in Propellers, (for which I have filed an application in the Netherlands on Aug. 5, 1918,) of which the following is a specification.

10 This invention relates to improvements in propellers for ships, floating structures, aeroplanes, torpedoes and the like.

The invention has for its object to construct a propeller with a higher efficiency 15 than the usual screw-propellers, so that as a consequence a ship, aeroplane or the like provided with a propeller according to the invention, can attain a higher speed with the same consumption of fuel and the same driving power.

According to the invention curved planes are arranged in such a manner that their rotation about the axis moves the medium particles of the fluid, through which the propeller travels, in a radial or almost radial direction and causes the reaction against this displacement to be transformed into a pressure in axial or almost axial direction. This and other features of the invention will be 20 more fully described hereinafter with reference to the accompanying drawings which form a part of my specification and application.

In the drawings:

35 Figure 1 is a perspective view of one form of my improved propeller.

Figs. 2 and 3 are similar views of modifications.

Fig. 4 is a plan view of another form of 40 propeller.

Figs. 5 and 6 are side and longitudinal sectional views, respectively, of the form shown in Fig. 4.

45 Figs. 7, 8 and 9 are views similar to Figs. 4, 5 and 6 but showing a modification of the form shown in the latter figures.

Figs. 10 and 11 are diagrammatic sectional and plan views, respectively, of a construction having oppositely rotating propellers.

50 Figs. 12 and 13 are similar views of a further modification.

In the embodiment illustrated in Fig. 1, a' is the body of the propeller having two radial cutting edges a^2 and two eccentric curved edges a^3 , each of the latter of which extend from the inner end of one cutting

edge to the outer end of the other cutting edge. Eccentrically curved planes a and b are provided at the curved edges and each of these planes is inclined rearwardly and outwardly and extends from the outer end of one cutting edge a^2 to the inner end of the other cutting edge.

With this construction, the propeller mounted on a driving shaft c , when moved in a direction to cause the cutting edges to cut the fluid, will trap volumes of fluid between the planes and body a' , and as the planes approach the axis toward their trailing ends, the fluid will be compressed and forced rearwardly near the axis. This causes the propeller to be moved forward.

The construction illustrated in Fig. 2 is similar to that shown in Fig. 1 with the exception that the propeller includes four cutting edges a^2 , four curved edges a^3 and four planes a and b .

The embodiment illustrated in Fig. 3 is similar to that shown in Fig. 2 with the exception that the outer edges of the planes are provided with outwardly extending segments b' .

Figures 1, 2 and 3 illustrate the principle of the invention and show the conical eccentric blades a, b which during their rotation about the axis of the shaft c form a space confined in three directions, said space being narrowed and enlarged respectively with respect to a line perpendicular to the shaft c . The effect of this construction is that fluid medium particles are displaced in radial direction toward the shaft, and moved into a gradually narrowing space, so that on account of their resistance against this radial displacement and this compression, they will give way and receive an increasing accelerated motion in consequence of which their reaction on the propeller blades remains constant. Moreover, those medium particles giving way being accelerated in all directions move along the planes a, b and exert on these planes an axial pressure in the direction of propulsion.

The propellers according to the invention are particularly adapted for use in water and air and have a higher efficiency than the usual screw propellers on account of the following advantages.

They make a profitable use of the fact that a pressure exerted on the medium is transmitted in all directions, and they transform into efficient power the counter currents and

radially directed forces resulting therefrom. With these propellers the property of resistance against compression is usefully applied in such a manner that in lieu of the 5 uniform motion of the medium particles as occurs with the screw propeller, a continuously increasing acceleration of those particles is obtained as the particles approach the axis, so that not only is the velocity in 10 axial direction increased with respect to that of the ordinary screw propeller, but it increases continuously as long as the conical-eccentric blades act upon the particles, so 15 that as a consequence these particles exert a constant pressure on all points of the body and planes.

In Figures 4 to 9, inclusive, I have illustrated high-pressure propellers, and referring particularly to Figs. 4, 5 and 6, the 20 body of the propeller is formed by two blades *f* and *g* arranged substantially at right angles to each other and each provided with straight side edges and eccentrically curved outer edges *f'*, which are provided 25 with eccentrically curved rearwardly and outwardly extending planes *d* and *e*. With this construction, the blades *f* and *g* will force the fluid rearwardly and outwardly while the planes *d* and *e* will force the fluid 30 inwardly, and when these currents of fluid meet they will move rearwardly and force the propeller forwardly.

The propeller illustrated in Figs. 7 to 9, inclusive, is similar to that in Figs. 4 to 6 35 with the exception that the planes are provided with outwardly extending segments *d'*.

In cases in which two propellers rotate about the same axis, as for instance in torpedoes, the embodiment illustrated diagrammatically in Figures 10 and 11 is very useful.

The object of this construction and arrangement is to exert a maximum pressure on the medium. In this instance the space mentioned above which gradually grows narrower, and which in the aforementioned case grows narrower only with respect to lines perpendicular to the axis of rotation, in the present case grows narrower literally. The trailing edges of the planes *h* namely of 45 the propeller rotating in the direction of the outer arrows are nearer the axis than the leading edges of said planes while the trailing edges of the planes *k* of the other oppositely rotating propeller are further away 50 from the axis than the leading edges thereof. It will be noted that the planes *h* are inclined rearwardly and outwardly and that the planes *k* are inclined rearwardly and inwardly.

55 In operation, when the planes of the propellers are passing each other, the distance between the outer and inner planes gradually diminishes, and the medium particles of fluid which are simultaneously rotated 60 and moved in axial direction will be caused

to move axially in an increasing degree as the trailing edges of the planes approach each other, and the reaction resulting therefrom will be increased as the medium particles give way more rapidly. In this construction, the planes *h*, *h* will cause the medium particles to approach the axis while the planes *k*, *k* will cause them to move away from the axis. During the rotation the points *r*, *s* will move in close proximity to 75 the points *x*, *y*, while the points *u*, *v* will pass at a much greater distance the points *w*, *z*.

In cases in which it is not possible to have two oppositely rotating propellers, a system 80 of stationary planes may be employed, which offer the possibility of obtaining, as in the last mentioned construction, spaces, growing narrower in literal sense, while the propeller rotates about this system of planes. 85

In Figures 12 and 13 I have illustrated such a system of planes with a propeller. The stationary planes *m* of this system as well as the blades *l* of the propeller are eccentrically placed with respect to the axis 90 *n*, and the centre of the system is disposed in axial alignment with the shaft of the propeller. The number of the planes *m* is arbitrary, and may be greater than the number of propeller blades *l*, as is the case in 95 the example shown.

The planes described could also be advantageously used with pumps and ventilators.

Having now particularly described and 100 ascertained the nature of my said invention, I declare that what I claim as new and desire to secure by Letters Patent is:—

1. A propeller including a blade having a helicoidal body provided with an eccentrically arranged rearwardly extending curved plane which extends entirely across the pressure side of the blade, the line of meeting between the pressure surfaces of the body and plane being eccentric to the axis 110 of the propeller.

2. A propeller of the kind defined by claim 1 in which the plane is inclined rearwardly and outwardly.

3. A propeller of the kind defined by 115 claim 1 in which the outer edge of the plane is provided with an outwardly extending segment.

4. A propeller including a plurality of blades each having a helicoidal body carrying an eccentrically arranged rearwardly extending curved plane which extends entirely across said body, said planes being inclined rearwardly and outwardly and provided at their outer edges with outwardly 120 extending segments.

5. A propeller comprising a hub, a plurality of blades carried by the hub and each having a helicoidal body, and an eccentrically arranged rearwardly extending plane 130

provided at the outer end of each of said bodies and extending entirely across the body, the lines of meeting between the bodies and planes on the pressure side of said 5 blades being eccentric relatively to the axis of the hub.

6. A propeller of the kind defined by claim 5 in which the planes are inclined rearwardly and outwardly.

10 7.. A propeller of the kind defined by claim 5 in which the planes are provided at their outer edges with segments.

8. A propeller for ships, floating structures, aeroplanes, torpedoes and the like, being totally immersed in the medium, having 15

the axis of rotation coinciding or almost coinciding with the direction of propulsion, comprising two propellers oppositely rotating about the same axis, one propeller having blades moving away from the axis of 20 rotation with respect to a line perpendicular to said axis, the other propeller having blades approaching said axis with respect to said perpendicular in such a manner, that during rotation the distance between the 25 blades of both propellers decreases or increases with respect to said perpendicular.

In testimony whereof I affix my signature.

EMANUEL SPREEKMEESTER.
